US0D1093384S

(12) **United States Design Patent** (10) **Patent No.:** **US D1,093,384 S**
(45) **Date of Patent:** **** Sep. 16, 2025**

(54) **MONITOR**

- (71) Applicant: **Samsung Electronics Co., Ltd.**, Suwon-si (KR)
- (72) Inventors: **Sangyoung Lee**, Suwon-si (KR); **Taeyeon Won**, Suwon-si (KR)
- (73) Assignee: **SAMSUNG ELECTRONICS CO., LTD.**, Gyeonggi-Do (KR)

(**) Term: **15 Years**

(21) Appl. No.: **29/877,846**

(22) Filed: **Jun. 13, 2023**

(30) **Foreign Application Priority Data**

- Dec. 29, 2022 (KR) 30-2022-0055215

(57) **CLAIM**

The ornamental design for a monitor, as shown and described.

DESCRIPTION

FIG. 1 is a front perspective view of a monitor, showing our new design;

FIG. 2 is a front view thereof;

FIG. 3 is a rear view thereof;

FIG. 4 is an enlarged left-side view thereof;

FIG. 5 is an enlarged right-side view thereof;

FIG. 6 is a top plan view thereof;

FIG. 7 is a bottom plan view thereof;

FIG. 8 is another perspective view thereof; and,

FIG. 9 is an enlarged view of the encircled portion 9 in FIG.

6.

The evenly dashed broken lines in the figures depict environmental subject matter and form no part of the claimed design.

The dot-dash broken lines encircling portions of the claimed design that are illustrated in enlargements form no part of the claimed design.

1 Claim, 9 Drawing Sheets
